ILLUMINATED STREET MARKER

Filed May 11, 1936

BY John W. Spellman
ATTORNEY.

UNITED STATES PATENT OFFICE

2,099,446

ILLUMINATED STREET MARKER

Frank B. Lockert, Dallas, Tex.

Application May 11, 1936, Serial No. 78,988

1 Claim. (Cl. 40—132)

The present invention relates to an improvement in illuminated street marker.

The invention further relates to new and useful improvements in street lamps and more particularly it pertains to a novel form of construction for lamp housings used in connection with street lighting apparatus.

It is a further object of the invention to so construct the lamp housing with panels bearing 10 information or other data which may be displayed by the housing or casing, and may be changed at will.

It is still a further object of the invention to provide a display stand which is permanent in 15 nature and which is also very attractive.

Another object of the invention is to provide a panel for the casing for indicating the block number.

A still further object of the invention is the 20 provision of a casing having display panels which may be interchanged at will.

The novel features that I consider characteristic of my invention are set forth with particularity in the appended claim. The invention itself, however, both as to its organization and its 25 method of operation, together with additional objects and advantages thereof, will be best understood from the following description of the specific embodiment when read in connection with the 30 accompanying drawing in which:—

Figure 1 is a side view of the improved street marker and display casing mounted on a supporting post.

Figure 2 is a sectional view taken on line 2—2 35 of Figure 1 showing the inside of the display casing and street marker.

Figure 3 is a sectional view taken on line 3—3 of Figure 1.

Referring in detail to the drawing, 10 represents 40 a metal post or pipe having a central opening 12 extending therethrough. The post 10 is mounted in a concrete base or standard 14. A casing 16 made preferably of metal is mounted or secured on the top of the post 10. The casing 16 has 45 four side portions 18, and a bottom 20. The top 22 of the casing 16 is tapered and is of pyramidal shape and comprises four sides 24. Each side portion 18 of the casing 16 has openings 26 and 28 for the reception of panels of glass 30 and 32 respectively. The sides 24 of the top 22 are also provided with openings 34 which are adapted to receive panels of glass 36.

Angular strips 38 may be made integral with the side portions 18 of the casing 16 or they may be 50 welded or otherwise secured thereto, and are

spaced at opposite sides of the openings 28 so as to form channels 39 for holding the panels of glass 32. There are angular strips 40 spaced at opposite sides of the openings 26 for holding the panels 30 in place in the openings. The openings 34 in the top 22 have angular strips 42 on two sides and larger angular strips 44 on the other two sides so that the panels of glass 36 are retained in position in the openings 34.

The bottom side 20 is provided with a central 10 opening 46. An incandescent lamp 48 extends through the opening 46 into the interior of the casing 16 and provides illumination. The numeral 50 indicates the electrical conductors connecting the lamp 48 to a source of energy (not 15 shown).

The panels of glass 36 carry markings to indicate the block number in a city. The panels of glass 30 bear a street marking, and the panels of glass 32 are provided with advertising or other 20 display matter. The panels 32 may be interchanged at will.

The lamp 48 illuminates the casing so that the street marking, the block number and also the advertising display can be seen at night even in a moving vehicle. The lamp 48 may be dispensed with, if desired. Each street intersection should be provided with four of the street markers 25 and/or display devices.

The display casing 16 may be placed in front 30 of cafes or other places of business or in the public parks.

My invention is to provide a street marker and display device which is both attractive and useful. Street markers of my improved design are cheaply manufactured, and it is obvious that my device 35 while shown to be illuminated may be constructed and used without the illuminating features as a street marker and display device for numerous purposes.

Although in accordance with the provision of the patent statute the invention is described as embodied in concrete form, it is to be understood that the apparatus shown in the drawing and described in the above specification is merely 40 illustrative and that the invention is not limited thereto since alterations and modifications will readily suggest themselves to persons skilled in the art without departing from the true spirit of the invention or the scope of the annexed claim. 45

What I claim and desire to secure by Letters Patent of the United States is:

In an illuminated street sign, a casing comprising a pyramidal-shaped top, a plurality of sides and a bottom portion, each side of the 55

pyramidal-shaped top having an opening provided with a panel of glass carrying a street number, each of the said sides having a square opening provided with a panel of glass carrying advertising matter, the said sides having a second opening of rectangular shape spaced above the said square opening and the rectangular opening provided with a panel of glass carrying a street

name, the said bottom of the casing having a central opening and an incandescent lamp extending through said opening into the casing for illuminating the panels of glass, and a supporting post to which the said bottom of the casing is secured. 5

FRANK B. LOCKERT.
